CODED TRACK CIRCUIT SIGNALING
SYSTEM

Thomas J. Judge, Rochester, N. Y., assignor to
General Railway Signal Company, Rochester,
N. Y.

Application September 7, 1942, Serial No. 457,545

21 Claims. (Cl. 246—3)

This invention relates to coded track circuit signaling systems for railroads, and it more particularly pertains to coded track circuit signaling systems for single track railroads used in combination with centralized traffic control.

The system of this invention is to be considered in the nature of an improvement over my prior application Ser. No. 365,669 filed November 14, 1940. Similarly, the system of this invention is to be considered in the nature of an improvement over the prior application of N. D. Preston, Ser. No. 439,520 filed April 18, 1942, as well as his prior Patent No. 2,342,489 granted February 22, 1944, on the application Ser. No. 455,328 filed August 19, 1942. It is to be understood that no claim is made in this application to any subject matter disclosed in the above mentioned prior applications.

The organization of the system provided by the present invention is such as to control the signals at the respective ends of passing sidings by the communication of distinctive signal controls from a control office to the location of such signals, the indications of the signals being also governed in accordance with traffic in advance by distinctive automatic signal controls transmitted through the track rails by coded track circuits. The apparatus grouped at each end of each of the passing sidings constitutes a field station. Controls are transmitted through the track rails by driven and inverse codes, a "driven code" being formed of time spaced impulses having their rate determined by the transmitter by which they are applied to the track rails, while an "inverse code" is formed of impulses transmitted during the "off" periods of a driven code applied at the exit end of the track section, the rate of the inverse code being determined by the rate of the driven code transmitted from the opposite end of that track section.

An object of the present invention is to govern the direction of track circuit code transmission in a stretch of track between two field stations by a traffic direction lever for such stretch at the control office, a change in the position of such lever being effective to initiate the checking of the unoccupied condition of each of the track sections before removing the code formerly transmitted by code transmitters through such respective track sections. Such condition is checked by the transmission in opposition to the driven code being transmitted of an abnormally long impulse through the track rails of each of the track sections, starting with the track section at the entrance end of the route according to the

prior established direction of track circuit code transmission.

Another object of the present invention is to follow up the abnormally long periods of energization for the various track sections by driven codes transmitted through the track rails for the direction of traffic desired to be established, the transmission of such driven codes being rendered effective for the various track sections in the stretch successively, starting with the track section at the entrance end of the route according to the prior established direction of track circuit code transmission.

Another object of the present invention is to allow both directions of traffic to be established at the same time for the respective ends of a single stretch of track when such stretch is occupied by a train as would be desirable for back-up train movements, the establishment of such directions being subject to the manual operation of the traffic direction lever for such stretch of track at the control office.

Another object of the present invention is to provide suitable means for restoring directional control relays for the signal locations of a stretch of track in correspondence with each other after they have become out of correspondence as, for example, in connection with back-up train movements.

Another object of the present invention is to control traffic direction relays at the various signal locations in such a manner as to cause them to be responsive to the reception of an abnormally long impulse transmitted through the track rails, but to be non-responsive to driven or inverse codes.

Other objects, purposes and characteristic features of the present invention will be in part obvious from the accompanying drawings and in part pointed out as the description of the invention progresses.

In describing the invention in detail, reference will be made to the accompanying drawings in which those parts having similar features and functions are designated throughout the several illustrations by like letter reference characters which are generally made distinctive by reason of preceding numerals indicative of the location or signal with which such parts are associated, and in which:

Fig. 1 illustrates control office apparatus for the communication of traffic direction and switch and signal controls to the respective field stations;

Figs. 2A through 2D when placed side by side

respectively illustrate the circuits employed for the control of the signals of this embodiment of the present invention, and the circuits employed in connection with the governing of code transmission in the various track sections;

Fig. 3 illustrates the manner in which approach locking is employed in this embodiment of the present invention;

Fig. 4 illustrates how the power operation of a track switch is effected in accordance with switch controls communicated from the control office; and

Figs. 5A through 5K (letter I omitted) illustrate diagrammatically conditions of track circuit code transmission through the various track sections under typical operating conditions.

The illustrations employed in the disclosure of this embodiment of the present invention have been arranged to facilitate the disclosure of the present invention as to the mode of operation and principles involved in the system rather than for the purpose of illustrating the construction and arrangement of parts that would be employed in practice. Thus the relays and their contacts are shown in a conventional manner, certain relay contacts being shown in written circuit form and identified as of particular relays by the reference characters appearing directly above such contacts.

The symbols (+) and (−) are employed to indicate the positive and negative terminals respectively of suitable batteries or other sources of direct current, and the circuits with which these symbols are used always have current flowing in the same direction.

The signal symbols used in the diagram of Figs. 5A through 5K (letter I omitted) are to be considered as indicative of the indications of the signals rather than the type of signals employed, the signals employed in this embodiment of the present invention being of the color light type. The signal arms of the symbols are relatively heavy and light to indicate the respective illuminated or dark conditions of the signals.

In order to simplify the description of the present invention, a general reference is made from time to time to functions common to all parts of a similar character by use in the description of letter reference characters without their preceding numerals. It is to be understood that such a reference applies to any parts designated in the drawings by reference characters that are similar except for preceding numerals associated therewith.

The trackway for which this embodiment of the present invention is provided comprises a main stretch of track (see Figs. 2A through 2D) divided into track sections, and having signals for governing traffic in both directions, such stretch of track having associated therewith at one end a passing siding A, and at the other end a passing siding B. The arrangement of the signals at each end of each of the passing sidings is provided in the usual manner to provide a short detector or OS track section for the track switch. The detector track section 7—8T, for example, is provided for the track switch 3W at the left-hand end of the passing siding B, and such track section has the usual type of steadily energized track circuit for the energization of the detector or OS track relay 1—8TR. The power operation of the track switch 3W by remote control can be provided as disclosed in detail, for example, in my prior application Ser. No. 365,669, dated November 14, 1940.

The signals at each of the field stations for governing passage of trains through the detector track section at such station are normally at stop and subject to manual control by an operator at the control office in any suitable manner such for example, as by the communication of controls by a coded centralized traffic control system such as disclosed in the patent to Judge et al., No. 2,082,544, dated June 1, 1937. The entering signals 8A and 8B at the left-hand end of the passing siding B, for example, govern east bound traffic (to the right) through the track section 7—8T, and the head-block signals 7A and 7B govern west bound traffic (to the left) through such track section. Similarly, the entering signals 1A and 1B govern west-bound traffic over the switch 2W in normal or reverse positions respectively; and head-block signals 2A and 2B govern east-bound traffic over the switch 2W in its normal and reverse positions respectively. The head-block signals are considered to be absolute signals, that is, a train must stop and stay when such signals indicate stop; while the other signals are assumed to be of the permissive type.

Intermediate signals are included between the passing sidings A and B, the signals 4 and 6 being provided for governing east bound traffic and the signals 3 and 5 being provided for governing west bound traffic.

Although the signals illustrated are of the color light type having individual color lamp units for the display of respective green (for clear), yellow (for caution), and red (for danger or stop) indications, it is to be understood that other types of signals such as searchlight, semaphore and position light signals could as well be employed.

Each of the track sections in the stretch of track between the passing sidings A and B has a coded track circuit which includes a track battery and a code following track relay TR at each end of the track section. For the purpose of obtaining the best operating conditions of the code following track relays it is desirable that each relay have a polar structure so arranged as to cause the relay contacts to be biased to a deenergized position from which they can be moved only upon energization of the relay windings with a particular polarity.

At each end of each of the track sections having a coded track circuit is a code transmitter relay CP which is operable when rendered active to transmit a 180 or 75 driven code, and, for certain of the track sections such relay can be at times active for the transmission of an inverse code. For purposes of obtaining the most desired operating characteristics of each of the relays CP, particularly when such relay is used as an inverse code transmitter, the relay has a polar structure to provide the operating characteristics above described as being preferable for the code following track relays TR.

Relays FP and FBP are provided for the ends of the track sections having coded track circuits, the relays FP being energized during the "on" periods of codes received, and the relays FBP being energized during the "off" periods of the codes received in such a manner as to detect the coding condition of the track circuit with which they are associated. Each of the relays is sufficiently slow in dropping away to be maintained picked up when a code is being received.

East and west directional stick relays EFR and WFR respectively are provided for each of the intermediate signal locations, and for each of

the field stations for maintaining a direction of driven code transmission in the track circuits to correspond with the position of the traffic lever 2-7FL at the control office. The relays EFR and WFR for each of the intermediate signal locations are sufficiently slow in picking up to allow their picking up only in response to a prolonged impulse transmitted through an associated coded track circuit.

Associated with each end of each of the track sections having a coded track circuit are H and D relays which are sufficiently slow acting to cause them to be maintained picked up when a code is being received. Each of the D relays is energized through the medium of a decoding transformer and a tuned circuit in a manner generally employed in coded track circuits so as to cause such relay to be picked up only in response to a 180 code. Each of the relays H, however, is picked up in response to a 75 or a 180 code, but only if it is a driven code that is received.

The relays EFR and WFR associated with the field stations are similar to those provided for the intermediate signal locations except for the relays 2WFR (at field station No. 1) and 7EFR (at field station No. 2) which are subject to the manual control of an operator at the control office. These relays 7EFR and 2WFR are sufficiently slow in dropping away to insure the establishing of their stick circuits which are interlocked with the traffic relays for the opposite directions.

Suitable code forming means is provided for the respective signal locations such, for example, as code oscillators or motor driven coders to form the different code rates employed. For this embodiment of the present invention an oscillator 180C is provided for each of the signal locations for forming a 180 code, and an oscillator 75C is provided at each of the signal locations for forming a 75 code.

Each of the field stations has office controlled relays for use in the manual control of the signals, a relay RGZ being provided for governing the clearing of signals for governing traffic to the right, and a relay LGZ being provided for governing the clearing of signals for governing traffic to the left. A stop relay B is associated with the relays RGZ and LGZ at each of the field stations to provide for the manual restoration to stop of a signal where a coded CTC communication system is employed for communication of signal controls from the control office to the respective field stations.

Associated with the control of the signals at each of the field stations are signal control relays AG and BG having their control circuits selected by correspondence relays NCR and RCR in the usual manner.

Having thus considered the structural organization of the system of this embodiment of the present invention a consideration will now be given to the mode of operation of the system under various typical operating conditions which would be encountered in practice.

Operation

General.—It is believed expedient before considering specifically the circuit organization provided for various parts of the system in order to provide the desired mode of operation to first consider with reference to the diagrams of Figs. 5A through 5K (letter I omitted) the general operating characteristics of the system and the utility of such characteristics.

- With reference to Fig. 5A, it will be noted that the conditions of code transmission are such as to transmit a driven code from left to right in each of the track sections having a coded track circuit, and to transmit an inverse code from right to left in the track sections 2-3T and 4-5T. The direction of driven code transmission is established to correspond with the position of the traffic direction lever 2-7FL (see Fig. 1) at the control office, such lever having been positioned for west bound traffic. Thus a relay WFR (see Figs. 2A through 2D) is picked up for each of the signal locations and the energized condition of such relay is effective to establish the direction of code transmission illustrated. The direction of driven code transmission is obviously established to clear signals for a west bound train, while the transmission of an inverse code in the track sections 2-3T and 4-5T is for the purpose of providing approach locking for the entering signal 1A, and for establishing means to provide an approach indication. With these conditions of code transmission effective, the signal 3 is at caution because the signal in advance is at stop, and the signal 5 is clear because of the signal 3 being at caution.
- It will be noted that the relay 2H (see Fig. 2A) at the left-hand end of the stretch of track between the passing sidings A and B is deenergized under the conditions illustrated because of the deenergized condition of the relay 2EFR, and thus it would be impossible for an operator at the control office to cause the clearing of signal 2A or signal 2B for governing east bound traffic in accordance with the reception at the left-hand end of track section 2-3T of the inverse code. In other words, the relay 2H can be picked up only by a driven code, and therefore the signals 2A and 2B can be cleared only by the transmission of a driven code in the direction of said signals in the track section 2-3T.
- A problem to be dealt with in the control of traffic direction relays is to provide a means to prevent the taking of a code away from a train if such train occupies the stretch of track between the passing sidings in an attempt to reverse the direction of driven code transmission. In order to prevent such a condition in this embodiment of the present invention it is provided that a code is removed from a track section upon a change in the position of the traffic direction lever at the control office, only upon the transmission of a prolonged or clear-out impulse through that track section in a direction corresponding to the movement of trains according to the previous direction of traffic established. The change in direction takes place for the track sections successively, starting with the track section adjacent the end of the stretch of track used as an entrance point for the traffic direction previously established.
- For example, if the direction previously established is for west bound trains as illustrated in Fig. 5A, and an operator attempts to reverse the direction of traffic by actuating his lever 2-7FL (see Fig. 1) to the right-hand position, a prolonged impulse is applied to the right-hand end of track section 6-7T without having removed the driven code normally transmitted from left to right in that track section.

- If the track section 6-7T is unoccupied, the reception of the prolonged impulse at the left-hand end of such section causes the cessation of the code transmitter relay 6CP for that end, thus establishing conditions which exist momentarily as illustrated in Fig. 5B in which a prolonged impulse is illustrated as being transmitted from

right to left in track section 6-7T to check the unoccupied condition of such section, and the reception of such impulse at the left-hand end of the track section causes the removal of the 180 driven code which has been transmitted from left to right in the track section according to the diagram of Fig. 5A.

A function of the prolonged or clear-out impulse, other than to cause the cessation of code transmission in the prior established direction, is to condition the traffic direction relays for the newly established traffic direction. Such conditioning is accomplished because the traffic direction relays are controlled in such a manner as to be responsive to a prolonged impulse as compared to their being non-responsive to code impulses of normal length. Thus, upon changing traffic direction as assumed above, the reception of the prolonged impulse at the left-hand end of the track section 6-7T is effective to cause the picking up of the relay 6EFR (see Fig. 2C) at the intermediate signal location at the left-hand end of the track section. The picking up of such traffic direction relay causes the dropping away of the relay 5WFR which has been energized according to the prior established direction, and the picking up of the relay 6EFR is also effective to initiate the transmission of a prolonged impulse through the adjacent track section 4-5T. In accordance with the reception of the prolonged impulse at the left-hand end of the track section 4-5T, the driven code which has been transmitted from left to right in that track section is removed as illustrated in Fig. 5C, and the traffic direction relays for the intermediate signal location at the left-hand end of the track section 4-5T are conditioned for the direction of traffic desired to be established. When such traffic direction relays are conditioned, the transmission of a prolonged impulse in the track section 2-3T is initiated, and the reception at the left-hand end of the track section 2-3T of such prolonged impulse is effective to cause the removal of the code which has been transmitted through such section in accordance with the prior established direction of traffic. The reception of the prolonged or clear-out impulse at the left-hand end of the track section 2-3T is effective to condition the traffic direction relays at that signal location in accordance with the desired traffic direction.

By the scanning of the track sections in the manner which has been described (starting with the entrance end for the previous direction of traffic) there is no possibility of causing an intermediate signal to go to stop in advance of a train on account of removal of code upon changing direction because each track section is checked for occupancy before the direction of code transmission is reversed.

The length of the prolonged or clear-out impulse transmitted through the track section adjacent the entrance end of the stretch of track, according to the prior established traffic direction, is determined by a timing device at such end to be of sufficient length to insure the proper response of the traffic direction relays for the various signal locations in the stretch of track. It will be noted as the description progresses that the length of the prolonged impulse transmitted through the track section adjacent such entrance end should be determined dependent upon the number of track sections in the stretch, as the circuit organization is such that the prolonged impulse for each of the successive track sections

is shortened in accordance with its remote relationship to the entrance end of the route according to the prior direction of traffic. Therefore, the prolonged impulse for the first track section 5 must be of such a duration as to cause the prolonged impulse for the last track section of the single track stretch to be of sufficient length to insure the proper response of the traffic direction relays for the extreme end of the single track stretch.

With reference to Figs. 5C and 5D, it will be seen that these prolonged impulses are applied to the successive track sections in overlapping relationships to insure a proper repeat of the impulses into each of the sections throughout the stretch. The system is thus so organized that, when the prolonged or clear-out impulse is made of greater duration in the first track section, the clear-out pulse in each of the remaining track sections is similarly made of greater duration. This is especially useful in cases where there may be a large number of successive track sections in the single track stretch and the duration of the prolonged or clear-out impulse for the first section must be of a substantial value, inasmuch as the timing for the clear-out pulse for the first section can be repeated to the other track sections without additional timing devices for each of the intermediate signal locations.

Immediately at the end of the prolonged impulse transmitted from the entrance end of the route according to the prior direction of traffic, a driven code is applied by the transmitter which has transmitted such prolonged impulse as illustrated in Fig. 5D. It will be noted that the application of such driven code is in accordance with the termination of the prolonged impulse in the first track section rather than being in accordance with the complete scanning of the stretch of track by the transmission of the prolonged impulses in the respective track sections. Similarly, in each of the track sections, the termination of the prolonged impulse transmitted through such section defines the beginning of driven code transmission through that track section in the newly established direction until the conditions of code transmission are established throughout the entire stretch of track as illustrated, for example, in Fig. 5E for the desired traffic direction.

The conditions of code transmission in the various track sections upon passage of a train are illustrated in Figs. 5F through 5K, and it is believed that such conditions will be more readily understood from the description as it will be herein-after set forth with respect to the specific circuit conditions involved upon the progress of a train.

The system provided by the present invention is particularly adapted to the control of intermediate signals for the provision of back-up train movements in that reversal in the direction of driven code transmission can be made effective in the rear of a train, and thereby provide control for signals governing a back-up train movement (see Fig. 5K). When a driven code is transmitted from each end of the stretch of track between the passing sidings as is the case when providing for a back-up train movement, or when an operator attempts to reverse the direction of traffic when a train is occupying the stretch of track between the passing sidings, it is necessary in order to establish one direction or the other for traffic through the stretch for an operator to position his traffic lever 2-7FL (see Fig. 1) to correspond with the direction of traffic desired

to be maintained and to press the cancel button 2-7CB for cancelling the opposing direction which has been established.

Normal conditions.—The conditions which are considered as normal are those conditions of the system in which the trackway is unoccupied by trains, the signals at the field stations are at stop, and the intermediate signals display proceed indications (see Fig. 5A) for one direction of traffic or the other in correspondence with the position of the traffic lever 2-7FL (see Fig. 1) at the control office. At the control office the switch control levers SML are illustrated as being in their normal positions, and the signal control levers SGL are illustrated as being normally in center positions in correspondence with the stop indication displayed by the signals at the respective field stations. The indicator lamps on the control panel are normally extinguished to correspond with the unoccupied condition of the trackway, except for the traffic direction indicator 2-7WFK which is illuminated in accordance with the direction of traffic established through the stretch of track between the passing sidings A and B, such direction being assumed to have last been established for the passage of west bound trains.

In that the manner in which the respective switch and signal and traffic direction controls are communicated from the control office to the respective field stations, and the manner in which the indications are communicated from the field stations to the control office has little bearing upon the present invention, for the purpose of simplification of the drawings, the communication of such controls has been merely indicated by dotted lines. It will be readily apparent that the arrangement of the circuits is such that the system is operative if the wires indicated as destined for stations Nos. 1 and 2 respectively are connected directly to wires designated by similar reference characters shown associated with the respective field stations. It is no doubt preferable, however, in most cases where the control office is located some distance away from the field stations that line wires be saved by the use of a code communication system for the communication of the controls such, for example, as is disclosed in the above mentioned Judge et al. patent, or as shown in the patent to Hailes et al., No. 2,259,561, dated October 21, 1941.

In accordance with the direction of traffic established for the passage of west bound trains, a traffic direction relay WFR at each of the signal locations is maintained picked up by a stick circuit closed at the back contact of the relay EFR for the opposite direction at that No. 1 location. For example, the relay 2WFR (see Fig. 2A) at the field station No. 1 at the left-hand end of the stretch of track between the passing sidings A and B is maintained picked up by an obvious stick circuit closed at back contact 40 of relay 2EFR. By such stick circuit control of the relay 2WFR, it will be noted that such relay can be deenergized only upon the picking up of the relay 2EFR for changing the traffic direction, relay 2EFR being responsive only to the transmission of a prolonged impulse from right to left through the track section 2-3T.

In accordance with the energized condition of the relay 2WFR under the conditions illustrated as normal, the relay 2CP is active for the transmission of a 75 driven code from left to right in the track section 2-3T because of the energization for each "on" period of the oscillator 75C of

a circuit extending from (+), including front contact 41 of relay 2WFR, contact 42 of oscillator 75C, back contact 43 of relay 1AG, front contact 44 of relay 2TJS, back contact 45 of relay 5 2TR, and winding of relay 2CP, to (-).

The closure of front contact 46 of relay 2CP for each impulse of the driven code causes the energization of an obvious track circuit for the relay 3TR (see Fig. 2B) including back contact 10 47 of relay 3CP at the right-hand end of track section 2-3T. The pulsing of contact 48 of relay 3TR causes the repeater relay 3TP to follow the code, and the pulsing of contact 51 of relay 3TP causes the relays 3FP and 3FBP to be maintained picked up. The relay 3FBP checks that a code is being received by the inclusion in its circuit of front contact 50 of relay 3FP, relay 3FP being energized by front contact 51 of relay 3TP, and relay 3FBP being energized by back contact 20 51 of relay 3TP with relay 3FP picked up.

The relay 3H is picked up in response to the 75 driven code by the energization for each impulse of that code of a circuit extending from (+), including front contact 51 of relay 3TP, 25 front contact 52 of relay 3FBP, front contact 53 of relay 3WFR, and winding of relay 3H, to (-). The closure of front contact 54 of relay 3H allows the energization of the decoding transformer 55, but the tuned circuit associated therewith 30 allows the picking up of the relay 3D only upon the reception of a 180 code. With the relay 3H picked up and the relay 3D dropped away, an obvious circuit is closed by which the yellow lamp of the intermediate signal 3 is energized at front 35 contact 56 of relay 3WFR.

For approach control purposes the relay 3CP is active to transmit an inverse code from right to left in the track section 2-3T when traffic is established for the passage of west bound trains, 40 such relay being picked up by the collapse of the flux in the transformer 57 at the end of each impulse of the driven code received. The primary winding of such transformer is energized for each impulse of the driven code received 45 at the right-hand end of track section 2-3T by a circuit extending from (+), including front contact 48 of relay 3TR, front contact 58 of relay 3WFR, front contact 59 of relay 4FBP, and primary winding of transformer 57, to (-). It will 50 be noted that the relay 3CP is active for the transmission of an inverse code only if front contact 59 of relay 4FBP is closed in accordance with the reception of an inverse code at the left-hand end of the track section 4-5T, thus providing 55 effectively an approach control portion of trackway including the track sections 2-3T and 4-5T. The relay 3CP, because of its polar structure, is responsive only to the collapse of flux in the transformer 57 by the energization of the secondary winding 60 of that transformer, the circuit including back contact 61 of relay 4EFR for the purpose of disconnecting the winding from the relay 3CP when such relay is employed as a driven code transmitter at a time when traffic direction is established for the passage of east bound trains.

Because of the caution indication of the intermediate signal 3, a 180 driven code is transmitted from left to right through the track section in the rear to cause the clear indication of signal 5. The relay 4CP is active for the transmission of such 180 driven code by the energization for each impulse of such code of a circuit extending from (+), including front contact 62 70 of relay 3WFR, contact 63 of oscillator 180C.

front contact 64 of relay 3H, front contact 65 of relay 3FBP, front contact 66 of relay 3FP, winding of relay 4CP, and back contact 67 of relay 4TR, to (-).

The reception at the right-hand end of track section 4-5T of the 180 driven code causes the relays 5FP, 5FBP and 5H (see Fig. 2C) to be picked up by the energization of circuits similar to those described for corresponding relays at the right-hand end of track section 2-3T. In accordance with the closure of front contact 68 of relay 5H, the decoding transformer 69 is effective to energize the tuned circuit for the relay 5D, and because of the 180 rate of the code, sufficient energy flows in the circuit to cause the relay 5D to be picked up. Because of the energized condition of the relays 5D and 5H, the green lamp G of signal 5 is energized by a circuit closed at front contact 70 of relay 5WFR.

The relay 5CP is active for the conditions under consideration for the transmission of an inverse code from right to left in the track section 4-5T in a manner similar to that which has been considered in the control of the relay 3CP for the transmission of an inverse code in the track section 2-3T. The primary winding of the inverse code transformer 71 is energized for each impulse of the driven code received at the right-hand end of the track section 4-5T by a circuit extending from (+), including front contact 72 of relay 5TR, front contact 73 of relay 5WFR, and primary winding of transformer 71, to (-). It will be noted from such circuit that inverse code transmission is effective in the track section 4-5T until such track section becomes occupied upon the passage of a west bound train.

In accordance with the clear indication of signal 5, the relay 6CP is active to transmit a 180 driven code from left to right in the track section 6-7T by the energization for each "on" period of the oscillator 180C of a circuit closed from (+), including front contact 74 of relay 5WFR, contact 15 of oscillator 180C, front contact 76 of relay 5H, front contact 77 of relay 5FBP, front contact 78 of relay 5FP, winding of relay 6CP, and back contact 79 of relay 6TR, to (-).

At the right-hand end of the track section 6-7T, the reception of the 180 driven code causes the pulsing of contact 80 of relay 7TR, and the relay 7TP following the code causes the pulsing of contacts 81 and 82 to cause the relays 7FP, 7FBP, 7T and 7D to be maintained picked up in a manner corresponding to that which has heretofore been specifically described for relays designated by similar letter reference characters. The energized condition of the relays 7H and 7D does not cause the clearing of the signal 7A or the signal 7B because of the manual control included in the circuits for such signals. It is believed to be readily apparent to those skilled in the art how the transmission of a control for the clearing of either of such signals becomes effective through the medium of an office controlled relay 7LGZ, signal 7A or signal 7B being selected by the correspondence relays 3NCR and 3RCR in accordance with the position to which the track switch 3W is operated.

Having thus considered the conditions in which the system exists when traffic direction is established for the passage of west bound trains, consideration will now be given to the establishment of the opposite direction of traffic.

Reversal in traffic direction.—To consider the

conditions effective upon a reversal in the direction of traffic, it will be assumed that an operator desires to establish a route for the passage of an east bound train. To initiate the establishment of such direction of traffic he actuates the traffic lever 2-7FL (see Fig. 1) to its right-hand position. The actuation of contact 83 of lever 2-7FL to its right-hand position opens an obvious circuit including wire 27 by which the relay 2WFR (see Fig. 2A) has been energized, but such relay is maintained picked up by its stick circuit. The closure of contact 83 of lever 2-7FL in its right-hand position through wire 28 causes the picking up of the relay 7EFR (see Fig. 2D) by the energization of an obvious circuit (or by a code communication system), and the picking up of such relay causes the dropping away of the relay 1WFR by opening its stick circuit at back contact 84. An obvious stick circuit is closed for relay 7EFR at back contact 165 of relay 1WFR.

The closure of front contact 85 of relay 7EFR with the relay 1TJS deenergized establishes a circuit by which the relay 7CP is energized for the transmission of a prolonged impulse such impulse being terminated after a time by the picking up of relay 1TJS as controlled by the slow pick-up relay 1TJ in a manner presently to be described. The circuit by which the relay 7CP is picked up extends from (+), including front contact 85 of relay 7EFR, back contact 86 of relay 1TJS, back contact 87 of relay 7TR, and winding of relay 7CP, to (-). The closure of front contact 88 of relay 7CP causes the track relay 6TR (see Fig. 2C) at the left-hand end of track section 6-7T to be picked up by the energization of an obvious circuit closed at back contact 89 of relay 6CP. The picking up of relay 6TR opens the circuit by which the relay 6CP has been active for the transmission of a driven code from left to right in the track section 6-7T at back contact 79, and thereby establishes a circuit by which the relay 6TR is energized continuously until the termination of the prolonged impulse transmitted from the right-hand end of the track section.

At the time the relay 7EFR is picked up at the right-hand end of the track section 6-7T for initiating the transmission of the prolonged impulse, a circuit is closed for the energization of the relay 1TJ (see Fig. 2D) which is provided for measuring the length of the prolonged impulse by its slow pick-up characteristics. Such circuit is closed from (+), including back contact 90 of relay 7CR, front contact 91 of relay 7EFR, back contact 92 of relay 1TJS, and winding of relay 1TJ, to (-). The slow operation of relay 1TJ can be provided in any suitable manner, such, for example, as by the use of a motor driven time element relay such as that disclosed in the O. S. Field patent, No. 2,199,335, dated April 30, 1940. After the relay 1TJ has completed its time of operation, the closure of front contact 93 of such relay causes the picking up of the relay 1TJS, and the picking up of such relay establishes a stick circuit by which it is maintained energized extending from (+), including back contact 90 of relay 7CR, front contact 91 of relay 7EFR, front contact 92 of relay 1TJS, and winding of relay 1TJS, to (-). The opening of back contact 92 of relay 1TJS in the circuit for relay 1TJ causes the restoration of relay 1TJ.

Upon the picking up of the relay 1TJS, the prolonged impulse is terminated by the opening

of back contact 86 in the circuit for relay 7CP, and the closure of front contact 86 of relay 7TJS provides for the relay 7CP to be active for the transmission of a 75 driven code (assuming the signal 8A to be at stop). The relay 7CP is active for the transmission of the 75 driven code under such conditions by the energization of a circuit for such relay for each "on" period of the oscillator 75C extending from (+), including front contact 85 of relay 7EFR, contact 94 of oscillator 75C, back contact 96 of relay 8AG, front contact 86 of relay 7TJS, back contact 87 of relay 7TR, and winding of relay 7CP, to (-). It has therefore been described how the relay 7CP is active for the transmission of a prolonged impulse followed by a driven code upon the picking up of the relay 7EFR for changing the direction of traffic.

At the left-hand end of the track section 6-7T, the reception of the prolonged impulse causes the relay 6FP (see Fig. 2C) to be picked up by the closure of front contact 97 of relay 6TP, but because of the sustained energization of the relay 6TP, the circuit for the relay 6FBP is maintained open at back contact 97 to prevent such relay from being picked up. Conditions are therefore established for the picking up of the relay 6EFR by the energization of the circuit extending from (+), including front contact 98 of relay 6FP, back contact 99 of relay 6FBP, and winding of relay 6EFR, to (-). The picking up of such relay opens the stick circuit by which the relay 5WFR has been maintained picked up at back contact 100 to cause the dropping away of such relay. When the relay 5WFR is dropped away, a stick circuit is closed at back contact 101 to maintain the relay 6EFR picked up. It will be noted from the pick-up circuit just described for the relay 6EFR, that the picking up of the relay 6FBP upon the reception of the newly applied driven code at the end of the prolonged period of energization will open the pick-up circuit for relay 6EFR at back contact 99.

Upon the picking up of the relay 6FBP in response to the driven code transmitted from right to left in the track section 6-7T following the prolonged impulse, a circuit is closed for the energization of the relay 6H extending from (+), including front contact 97 of relay 6TP, front contact 102 of relay 6FBP, front contact 103 of relay 6EFR, and winding of relay 6H, to (-). Upon the picking up of relay 6H, an obvious circuit is closed for the energization of the yellow lamp Y of signal 6; such circuit having energy applied at front contact 104 of relay 6EFR.

At the time when the relay 6EFR is picked up, a circuit is closed for the energization of the relay 5CP for the transmission of a prolonged impulse in the track section 4-5T. Such circuit extends from (+), including front contact 105 of relay 6EFR, back contact 106 of relay 6FBP, front contact 107 of relay 6FP, winding of relay 5CP, and back contact 108 of relay 5TR, to (-). It will be noted from the circuit just described that the prolonged period of energization of the relay 5CP is terminated by the picking up of the relay 6FBP in response to the newly applied driven code in the track section 6-7T. The picking up of such relay opens the circuit for relay 5CP at back contact 106 and closes a circuit by which the relay 5CP becomes active for the transmission of a 180 driven code in the track section 4-5T. Such circuit extends from (+), including front contact 105 of

relay 6EFR, contact 109 of oscillator 180C, front contact 110 of relay 6H, front contact 106 of relay 6FBP, front contact 107 of relay 6FP, winding of relay 5CP, and back contact 108 of relay 5TR, to (-).

At the left-hand end of the track section 4-5T, the reception of the prolonged impulse transmitted through such track section causes the picking up of the relay 4EFR (see Fig. 2B) 10 in a manner similar to that which has just been described in connection with the picking up of the relay 6EFR, and the picking up of such relay causes the dropping away of the relay 3WFR by opening its stick circuit at back contact 111. The 15 dropping of relay 3WFR closes the stick circuit for relay 4EFR at back contact 112 to complete the change in the conditioning of the traffic direction relays for that intermediate signal location. Upon the closure of front contact 113 of 20 relay 4FBP in response to the newly established driven code, the relay 4H is picked up, and the closure of front contact 114 of such relay renders the pulsing of contact 115 of relay 4TP effective to cause the relay 4D to be picked up in response 25 to the 180 driven code transmitted from right to left in the track section 4-5T following the prolonged period of energization of the track circuit. When these relays have been picked up, an obvious circuit is closed for the energization of 30 the green lamp G of signal 4 at front contact 116 of relay 4EFR.

Upon the picking up of the relay 4EFR, a circuit is closed for the energization of the relay 3CP for the transmission of a prolonged impulse 35 in the track section 2-3T corresponding to that which has been described in connection with the energization of the relay 5CP for the transmission of a prolonged impulse in the track section 4-5T, the impulse transmitted by the relay 3CP being terminated by the picking up of the relay 4FBP when the newly established code is received at the left-hand end of track section 4-5T. When such code is received the relay 4H is picked up, and thus the relay 3CP becomes 40 active for the transmission of a 180 driven code from right to left in the track section 2-3T by the energization of a circuit extending from (+), including front contact 117 of relay 4EFR, contact 118 of oscillator 180C, front contact 119 45 of relay 4H, front contact 120 of relay 4FBP, front contact 121 of relay 4FP, winding of relay 3CP, and back contact 122 of relay 3TR, to (-).

At the left-hand end of track section 2-3T, the energization of the relay 2TR (see Fig. 2A) 50 during the prolonged impulse causes the dropping away of the relay 2FBP because of the failure to close a circuit for such relay at back contact 123 of relay 2TP. A pick-up circuit is then established for the relay 2EFR extending from (+), including front contact 124 of relay 2FP, back contact 125 of relay 2FBP, and winding of relay 2EFR, to (-), to cause such relay to be picked up, and by the opening of its back contact 40 to cause the release of the relay 2WFR. The dropping away of the relay 2WFR completes the conditioning of the traffic direction relays for the establishment of east bound traffic. The pick-up circuit for relay 2WFR is open because of the right-hand position to which the operator has been assumed to have operated the traffic direction lever 2-7FL (see Fig. 1) at the control office.

The relay 2H (see Fig. 2A) is picked up in accordance with the closure of front contact 126 of relay 2EFR when the newly established 75

driven code is received at the left-hand end of the track section 2—3T. In accordance with the closure of front contact 127 of relay 2H, the pulsing of contact 128 of relay 2TP is effective to cause the picking up of the relay 2D by the energization of its circuit tuned to the 180 rate. With the relays 2H and 2D picked up, it will be readily apparent that conditions are established whereby signal 2A or signal 2B can be cleared by manual control upon the positioning of the signal control lever belonging to such signals at the control office.

It will be noted that there is no inverse code transmitter at the left-hand end of the track section 2—3T, and therefore there is no inverse code transmitted from left to right in such section. Thus the relays 3FP, 3FBP, 3H and 3D (see Fig. 2B) are deenergized for east bound traffic, and the opening of front contact 56 of relay 3WFR causes the signal 3 to be dark.

The closure of front contact 129 of relay 4EFR in the circuit for the primary winding of the transformer 133 renders the relay 4CP active for the transmission of an inverse code from left to right in the track section 4—5T. The primary winding of such transformer is energized for each driven code impulse received by the relay 4TR by a circuit closed from (+), including front contact 130 of relay 4TR, front contact 129 of relay 4EFR, and primary winding of transformer 133, to (—). The back contact 131 of relay 3WFR is closed to connect the secondary winding of the transformer 133 across the winding of the relay 4CP to render such relay active for the transmission of an inverse code.

The reception of the inverse code at the right-hand end of the track section 4—5T causes the energization of the relays 5FP and 5FBP (see Fig. 2C), but the relays 5H and 5D are deenergized because of the opening of the circuit for relay 5H at front contact 132 of relay 5WFR. Because of the reception of the inverse code at the right-hand end of track section 4—5T, the relay 6CP becomes active for the transmission of an inverse code from right to left in the track section 6—7T. Such inverse code is transmitted because of the energization of the primary winding of the transformer 134 for each driven code impulse received by relay 6TR, a circuit for the primary winding of the transformer being closed each time the relay 6TR is picked up from (+), including front contact 135 of relay 6TR, front contact 136 of relay 6EFR, front contact 137 of relay 5FBP, and primary winding of transformer 134, to (—).

At the right-hand end of the track section 6—7T, the reception of the inverse code causes the relays 7FP and 7FBP (see Fig. 2D) to be picked up, but the relays 7H and 7D are dropped away because the circuit for relay 7H is open at front contact 138 of relay 7WFR. The maintaining of the relay 7FP picked up by the inverse code closes an obvious circuit at front contact 139 to maintain the approach relay 8AR energized, and the energized condition of the relay 7FBP because of the reception of a code holds the pick-up circuit opened for the relay 7WFR at back contact 140. It will be noted that the relay 8AR has been held up by its stick circuit for the duration of the prolonged impulse transmitted from that end of the stretch of track. Such stick circuit is closed upon the picking up of relay 7EFR and extends from (+), including front contact 141 of relay 7EFR, back contact 142 of relay 7TJS, front contact 143 of relay 8AR, and wind-

ing of relay 8AR, to (—). Back contact 142 of relay 7TJS is opened upon the termination of a prolonged impulse transmitted from that end of the stretch. Thus by this arrangement, in combination with relatively slow acting characteristics of the relay, the relay 8AR is deenergized only when either track section 4—5T or 6—7T is occupied by an east bound train.

Passage of a train.—To consider the mode of operation of the system upon passage of a train, it will be assumed that the conditions of the system are initially as illustrated in Fig. 5A and as described when considering the normal conditions of the system, with traffic direction established for the passage of west bound trains. It will be assumed that a west bound train approaches the signal 1A at the left-hand end of the passing siding B (see Fig. 5F), and that an operator at the control office actuates the signal control lever 7—8SGL (see Fig. 1) to its left-hand position to cause the clearing of such signal.

With the lever 7—8SGL in its left-hand position, a circuit is closed at contact 144 to apply energy to wire 32 for the communication of a control to the field for causing the picking up of the relay 7LGZ (see Fig. 2D). If such relay is picked up by a code communication system, the energization of the wire 32 for its pick-up circuit is only momentary, and a stick circuit is established for the relay in a manner fully disclosed in my prior application, Ser. No. 365,669, filed November 14, 1940.

Upon the picking up of the relay 7LGZ, a circuit is closed to cause the picking up of relay 7AG extending from (+), including front contact 145 of relay 7—8TR, front contact 146 of relay 3NCR, back contact 147 of relay 3RCR, front contact 148 of relay 7LGZ, front contact 149 of relay 7WFR, front contact 150 of relay 7H, and winding of relay 7AG, to (—). The picking up of relay 7AG, by the shifting of contact 151 causes the extinguishing of the red lamp R of signal 1A, and causes the energization of the green lamp G of such signal in accordance with the energized condition of the relay 1D.

Upon accepting the signal 1A, the entrance of the train into the track section 7—8T causes the restoration of the signal to stop in the usual manner, the relay 7LGZ being dropped away because of the opening of its stick circuit if the signals are controlled as stick signals as disclosed in my above mentioned prior application.

When the train enters the stretch of track between the passing sidings A and B (see Fig. 5A), there is no APB tumble-down to be effected because such condition has already been taken care of by the directional stick relays for the intermediate signal locations, the opposing signals being not only conditioned to display stop indications, but being dark as selected by the directional control relays.

When the west bound train progresses to a point, however, where it enters the track section 4—5T (see Fig. 5H), the shunting of such track section causes the dropping away of the relays 4FP and 4FBP (see Fig. 2B) which have been held up by the inverse code, and the opening of front contact 59 of relay 4FBP in the circuit for the primary winding of transformer 57 renders the relay 3CP inactive for the transmission of an inverse code from right to left in the track section 2—3T.

The cessation of the inverse code in the track section 2—3T causes the dropping away of the

relays 2FP and 2FBP (see Fig. 2A), and the dropping away of the relay 2FP causes the approach control relay 1AR to be dropped away upon the opening of front contact 152. The dropping away of relay 1AR closes back contact 153 to provide for the application of energy to wire 21 for the illumination of the approach indicator lamp 1AK (see Fig. 1) at the control office. The dropping away of the relay 1AR opens the approach locking contact 154 (see Fig. 3) in the control of the approach locking relay 1AS associated with signals 1A and 1B. By such arrangement it is provided that the changing of the position of the track switch 2W can be effected only after a predetermined time interval if a route has already been established over the track switch. This is in accordance with the usual desired mode of operation in providing approach locking, the time interval being required only when the approach section is occupied by a train as detected by the approach relay 1AR.

When the track section 6-7T becomes unoccupied in the rear of the train, the transmission of a 75 driven code by the relay 6CP is effective to provide a caution indication for the passage of a following train, dependent of course upon the manual control of the signals 1A and 1B. The circuit by which relay 6CP is energized for each impulse of the 75 code extends from (+), including front contact 14 of relay 5WFR, contact 155 of oscillator 75C, back contact 156 of relay 5FBP, back contact 18 of relay 5FP, winding of relay 6CP, and back contact 19 of relay 6TR, to (-). It will be noted that the usual type of directional stick relay generally employed at intermediate signal locations is not required to select the transmission of the code for a following train, because the transmission of such code is rendered effective by the directional stick relay 5WFR which is a traffic direction relay that is unaffected by the passage of trains, such relay being controlled only by prolonged periods of energization of the track circuit initiated by manual control from the control office.

For the purpose of simplification of the disclosure of the present invention, details have not been shown for the control of the relays 1D and 1H for the main track section 1T associated with the passing siding A, however, it is to be understood that such relays can be controlled either by coded track circuits, as indicated in the drawings, or by line wire control, in accordance with the condition of occupancy of the track section 1T and in accordance with the indication of the next signal in advance. For convenience in the disclosure, it is assumed that coded track circuit control is provided for the siding sections 1T and 8T, and although no effort has been made to disclose such coded control, it has been assumed to be of the type shown in my prior application Ser. No. 455,922, filed August 24, 1942, so as to facilitate the showing of the contacts of certain relays, such as relays 1H, 1D, 8H, 8D, required in the control of the signals illustrated in the present disclosure. In other words, the Figs. 2D and 2A placed side by side in that order with coded track circuit apparatus provided for the siding section (thus formed), the same as the coded track circuit apparatus shown for the siding section in my above mentioned application provides a complete system within the scope of this invention. In this way, the signals 1 and 8 are properly interlocked and means is provided to govern the approach locking relays 2AS and 7AS of Fig. 3. It is thus believed to be sufficient

for the purposes of the present disclosure to know that the relays 1H and 8H, corresponding to similar H relays in my prior application, are normally picked up; while the relays 1D and 8D, corresponding to similar relays in my prior application, are normally dropped away. Also, the clearing of the signal 1A would effect the dropping away of the relay 8H; and similarly, the clearing of the signal 8A would cause the dropping away of the relay 1H. More specifically, with the relay 1H picked up, then the signal 1A may be caused to indicate caution which effects the dropping away of the relay 8H and ultimately the picking up of the relay 1D dependent upon the indication of the signal 1A. It is thus understood how the relays 1D and 1H may both be picked up.

Assuming the relays 1D and 1H to be picked up, an operator at the control office can cause the clearing of signal 1A and thus cause the transmission of a 180 driven code from left to right in the track section 2-3T for the clearing of signal 3, if the signal control lever 1-2SGL (see Fig. 1) at the control office is actuated to its left-hand position. The application of energy to the wire 22 under such conditions causes the picking up of the relay 1LGZ (see Fig. 2A), and the picking up of such relay, with the track switch 2W in its normal position, closes a circuit for the energization of the signal control relay 1AG extending from (+), including front contact 157 of relay 1-2TR, front contact 158 of relay 2NCR, back contact 159 of relay 2RCR, front contact 160 of relay 1LGZ, front contact 161 of relay 1H, and winding of relay 1AG, to (-). The shifting of contact 162 of relay 1AG causes the extinguishing of the red lamp R of signal 1A, and causes the energization of the green lamp G of such signal with the relay 1D picked up.

The picking up of the relay 1AG with the relay 1H picked up, by the shifting of contact 43 changes the driven code transmitted from left to right in track section 2-3T from a 75 code to a 180 code. The reception at the right-hand end of the track section of the 180 code causes the picking up of the relay 3D (see Fig. 2B), and the picking up of such relay upon the shifting of contact 163 causes the extinguishing of the yellow lamp Y of signal 3 and the energization of the green lamp G of such signal.

As the west bound train progresses further so as to leave the track section 4-5T unoccupied in the rear of the train (see Fig. 5J), a 75 driven code is transmitted by the relay 4CP in the track section 4-5T in accordance with the closure of back contacts 164 and 66 of relays 3FBP and 3FP respectively. At the right-hand end of the track section 4-5T the conditions are restored to normal except for the relay 5D (see Fig. 2C) which remains deenergized because of the 75 code being received, such relay in its deenergized condition selecting the energization of the yellow lamp of signal 5. The picking up of relay 5H in combination with the picking up of relays 5FBP and 5FP closes a circuit by which the relay 6CP is active for the transmission of a 180 driven code in the track section 6-7T to restore the normal conditions for such track section.

Further progress of the west bound train into the track section 1T allows restoration to stop of the signal 1A, and, when the track section 2-3T becomes unoccupied in the rear of the train, the normal conditions of code transmission are restored for such track section by the

energization of circuits which have been described when considering the normal conditions of the system. The reception at the right-hand end of the track section 2-3T of the 75 code causes the restoration to normal conditions at the intermediate signals 3 and 4 to provide for the transmission of a 180 driven code in the track section 4-5T for causing the illumination of the green lamp of signal 5, thus completing the restoration to normal conditions after the passage 10 of the train, as indicated in the diagram of Fig. 5A.

Back-up train movements.—A desirable feature of the present invention lies in the provision for back-up train movements, particularly in that the intermediate signals are subject indirectly to manual control of an operator at the control office for making such back-up train movements possible. To consider specifically a typical condition, it will be assumed that a west bound train 15 has occupied the track section 4-5T, and the track section 6-7T has become unoccupied in the rear of the train (see Fig. 5H).

It has been described that under such conditions a 75 driven code is transmitted from left to right in the track section 6-7T in accordance with the energized condition of the traffic direction relay 5WFR (see Fig. 2C) at the intermediate signal location. Because of the de-energized condition of the traffic direction relay 6EFR, the signal 6 is dark in accordance with its circuit having been opened at front contact 104. Under such conditions it will be assumed that an operator desires to cause the train to proceed in the direction of the passing siding B. The conditions involving the reversal in the direction of traffic in accordance with the regulations of the railroads as to the communication between the trainman and the operator at the control office would necessarily be complied with; but, the extinguishing of the approach indicator lamp 8AK (see Fig. 1) on the control panel at the control office would indicate to the operator that the track section 6-7T were unoccupied in the rear of the train, and thus it would be possible to control the signal 6 for a back-up train movement.

To cause the signal 6 to display a proceed indication for a back-up train movement and set up conditions indicated in Fig. 5K, it will be assumed that an operator actuates the lever 2-7FL on the control panel to the right-hand position for the establishment of east bound traffic. In accordance therewith, the contact 83 of the lever 2-7FL applies energy to wire 28 to cause the picking up of the relay 1EFR (see Fig. 2D) at passing siding B. The picking up of such relay causes the dropping away of the relay 1WFR by opening its stick circuit at back contact 84, and the dropping away of relay 1WFR establishes a stick circuit for relay 1EFR closed at back contact 165. It will be readily recognized that this is the beginning of a cycle of operation corresponding to that which has been described when considering the mode of operation of the system upon changing traffic direction during which a prolonged impulse is transmitted in the track section 6-7T, followed by the transmission of a 75 driven code (assuming signal 8A to be at stop).

The reception of the prolonged impulse at the left-hand end of the track section 6-7T causes the picking up of the relay 6EFR and the dropping away of relay 5WFR, and the relay 6H is picked up by the 75 driven code which follows

the prolonged impulse. Upon the picking up of relay 6H, an obvious circuit is closed at front contact 166 for the energization of the yellow lamp of signal 6 to display a caution indication for a back-up train movement. Front contact 104 is closed because of the response of the relay 6EFR to the long impulse transmitted through the track rails.

It is believed to be readily apparent that the signal 6 could be controlled to display a clear indication in accordance with the transmission of a 180 driven code from right to left in the track section 6-7T if the signal 8A were controlled to indicate proceed. It will be noted at this point that the system is adapted to allow the control of signals for back-up train movements either with or without controlling the signals at the ends of the stretch of track.

Correspondence of traffic direction relays.—There are certain conditions when the traffic direction relays for the respective signal locations become out of correspondence with each other. One condition is that just described above where the control of signals for back-up train movements is provided. Under such conditions, when the stretch of track becomes unoccupied after passage of a train, the traffic direction relays for certain of the signal locations, particularly the locations for the extreme ends of the stretch of track, are out of correspondence; and therefore driven codes are transmitted through the respective end sections in the direction of the intermediate track section 4-5T.

Upon considering the circuits for the traffic direction relays EFR and WFR for the field stations at the ends of the stretch of track between the passing sidings A and B, it will be noted that a change in the condition of the traffic direction relays can be accomplished only by the transmission of a prolonged impulse through the track rails. Thus, to restore the traffic direction relays in correspondence for the establishment of a particular direction of traffic, the traffic direction lever 2-7FL (see Fig. 1) at the control office is positioned as desired, and the traffic correspondence button 2-7CB is depressed. The depression of such button applies energy to contact 167 of lever 2-7FL, and if the lever is positioned for west bound traffic, energy is applied to wire 26 for the communication of a control to cause the momentary energization of the relay 2CR at the field station associated with passing siding A.

The picking up of relay 2CR, under such conditions, opens the stick circuit for relay 2TJS at back contact 168 to cause such relay to be dropped away. The stick circuit by which the relay 2TJS has been energized corresponds to the stick circuit which has been described for relay 1TJS at the opposite end of the stretch. With relay 2TJS dropped away, a circuit is closed at back contact 44 to energize the relay 2CP for the transmission of a prolonged impulse. Because of the relay 2CR being only momentarily picked up, the closure of back contact 168 of such relay establishes a circuit for the slow pick-up relay 2TJ for measuring the length of such prolonged impulse, such circuit corresponding to a circuit which has been described for relay 1TJ at the opposite end of the stretch.

Upon the reception of the prolonged impulse at the right-hand end of track section 2-3T, the traffic direction relays 3WFR and 4EFR are conditioned as they would be ordinarily upon a reversal in traffic direction, unless they are al-

ready in correspondence with the relays at the right-hand end of the stretch of track. After the traffic direction relays have been properly conditioned at the intermediate signal location of signals 3 and 4, a prolonged impulse, followed by a driven code is transmitted in the track section 4-5T, and in each other track section successively until the traffic direction relays for each of the signal locations are conditioned to correspond with the traffic direction relays at the left-hand end of the stretch of track.

Another condition under which a similar mode of operation would be required for the establishment of correspondence between the traffic direction relays would be a condition where an operator inadvertently moved the traffic direction lever 2-7FL when the stretch of track between the passing sidings A and B were occupied by a train. Under such conditions, the system would attempt to change direction for each track section successively in the rear of the train, but at some point the prolonged impulse would lose out because of failure to transmit under the train. Thus, when the track section would become unoccupied after passage of the train, whether such train had reversed its direction or not, some of the traffic direction relays for the stretch would be out of correspondence. It will be readily apparent that the remedy for such a condition is to select the desired direction of traffic by the lever 2-7FL as has been described and depress the correspondence button 2-7CB.

Approach locking.—The system according to the present invention is adapted by the use of inverse code to provide for approach control in connection with the signals governing entrance to the respective siding sections, such control extending for two track sections in the rear of such entering signals. As for the circuits involved in the control of the approach locking relays AS associated with the respective office controlled signals at the field stations, it is to be understood that various forms of control can be provided in accordance with the requirements of practice, such forms being well-known to those familiar with the art.

One form is illustrated, for example, in Fig. 3 in which the relay 1AS provided for the signals 1A and 1B is normally energized by a stick circuit extending from (+), including front contact 169 of relay 1M, winding of the thermal relay 1TH, front contact 170 of relay 1AS, and winding of relay 1AS, to (-). The opening of back contact 171 of relay 1AG or back contact 172 of relay 1BG in the clearing of signal 1A or signal 1B would cause the dropping away of relay 1M, and the dropping away of such relay would cause the release of the relay 1AS because of the opening of front contact 169.

Upon the manual restoration of either signal 1A or signal 1B to stop before such signal has been accepted by a train, the relay 1M becomes energized to close front contact 169 in the circuit of relay 1AS, and the relay 1AS can be picked up immediately if front contact 154 of the relay 1AR is closed, such circuit extending from (+), including front contact 169 of relay 1M, front contact 154 of relay 1AR, and winding of relay 1AS, to (-). The relay 1AR (see Fig. 2A), however, can be energized only if the track sections 2-3T and 4-5T are unoccupied by a west bound train. Thus, upon the entrance of a west bound train into the track section 4-5T, the inverse code would be removed from the track sections 4-5T and 2-3T, and the

removal of such code by causing the dropping away of relay 2FP (see Fig. 2A) at the left-hand end of the stretch would effect the opening of the circuit for relay 1AR at front contact 152, thus causing such relay to be dropped away. In accordance with the opening of the approach control restoration circuit for relay 1AS (see Fig. 3) at front contact 154 of relay 1AR, the restoration of relay 1AS could be effected only after a predetermined time measured by the thermal relay 1TH, such thermal relay being energized by a circuit extending from (+), including front contact 169 of relay 1M, winding of thermal relay 1TH, and back contact 170 of relay 1AS, to (-). At the end of such predetermined time, the relay 1AS would be picked up by a circuit extending from (+), including front contact 169 of relay 1M, contact 173 of thermal relay 1TH closed in its operated position, and winding of relay 1AS, to (-). The picking up of the relay 1AS under such conditions would open the circuit by which the thermal relay 1TH is active at back contact 170, and close a normally energized stick circuit which has been described. When the signal 1A or 1B is put to stop automatically upon passage of a train past such signal, the closure of back contact 174 of the OS track relay 1-2TR causes the immediate restoration of the relay 1AS by the energization of an obvious circuit which is closed upon the restoration of the relay 1M to its normally energized position.

The approach locking relays in this disclosure have their contacts including directly in the switch machine operating circuits as illustrated in Fig. 4, but it is to be understood that they could as well be included indirectly through the medium of a lock relay in accordance with the requirements of practice. It will be noted in Fig. 4 that the relay 1AS, for example, has front contacts 177 and 178 included in the normal and reverse control circuits respectively of the switch machine 2SM for the power operation of the track switch 2W.

Having thus considered specifically the conditions with respect to the approach locking for a particular one of the manually controlled signals at a field station, it is to be understood that the conditions described are typical of those conditions associated with the approach locking provided for the other manually controlled signals disclosed in this embodiment of the present invention.

Indications.—The relays 1AR (see Fig. 2A) and 8AR (see Fig. 2D) for the respective left and right-hand ends of the stretch of track between the passing sidings A and B are also employed in the provision of approach indications at the control office, such relays being energized except when their respective approach sections are occupied by a train proceeding in either direction. Thus, the relay 1AR, for example, being dependent for its energization upon the reception of code transmitted from right to left in the track sections 4-5T and 2-3T, is dropped away whenever either of such track sections are occupied by a train proceeding in the direction of the passing siding A. In accordance with the deenergization of the relay 1AR, the closure of back contact 153 applies energy to wire 21 for communication of a control to the control office for causing the energization of the indicator lamp 1AK (see Fig. 1).

If the track section 2-3T were occupied by

an east bound train, the relay 2FP would be dropped away, and the opening of front contact 152 under such conditions would cause the closure of back contact 153 of relay 1AR for the communication of a control over wire 21 to the control office for the energization of the approach indication lamp 1AK. If an east bound train were to proceed so as to cause the track section 2-3T to become unoccupied by the train; however, the transmission of a 75 code from right to left in the track section 2-3T as selected by the energization of the relay 4EFR (see Fig. 2B) to close front contact 117 in the circuit for relay 3CP would cause the picking up of the relay 2FP (see Fig. 2A) at the left-hand end of the track section, and the picking up of that relay upon the closure of front contact 152 would cause the energization of the relay 1AR for the extinguishing of the lamp 1AK in accordance with the opening of back contact 153. It will therefore be seen that the indicator lamp 1AK, for example, is illuminated whenever a west bound train occupies either track section 4-5T or track section 2-3T, but is illuminated upon the passage of an east bound train only when such train occupies the track section 2-3T.

A stick circuit is provided for the relay 1AR and for the relay 8AR to prevent the illumination of the respective approach indicator lamps 1AK and 8AK at the control office momentarily upon the changing in traffic direction through the stretch of track between the passing sidings A and B. The manner in which such stick circuit is employed has been described in detail with respect to the control of the relay 8AR when considering the mode of operation of the system with respect to reversal in the direction of traffic.

It will be noted in Fig. 1 that in addition to the approach indicator lamps, OS indicator lamps 1-2TK and 7-8TK are provided in the manner commonly employed in practice to indicate occupancy of the respective detector track sections.

The traffic direction lamps 2-7WFK and 2-7EFK provided at the control office for indicating the direction of traffic established in the stretch of track between the passing sidings are governed in accordance with the conditions of the traffic direction relays for the respective ends of the stretch of track between the passing sidings. Thus, the lamp 2-7WFK is normally illuminated because of the closure of front contact 175 of relay 2WFR (see Fig. 2A) to apply energy to the wire 25 for communication to the control office for the energization of that lamp. Upon changing traffic direction, the operation of the lever 2-7FL to its right-hand position by an operator would cause the picking up of the relay 7EFR (see Fig. 2D) in accordance with the application of energy to wire 28 in a manner which has been described, and the picking up of such relay would close front contact 176 to apply energy to wire 30 for the communication of a control to the control office for the energization of the traffic direction lamp 2-7EFK (see Fig. 1). Under such conditions both traffic direction lamps will be momentarily illuminated as the extinguishing of the lamp 2-7WFK is dependent upon the dropping away of the relay 2WFR to open its control circuit at front contact 175. The dropping away of the relay 2WFR upon changing the direction of traffic as above assumed, could be effected only after the transmission of an abnormally long impulse through

the track sections of the stretch successively, starting at the right-hand end of the stretch, so as to cause the picking up of the relay 2EFR (see Fig. 2A), the picking up of which would be effective to open the stick circuit for the relay 2WFR at back contact 40 and cause the release of that relay. The release of relay 2WFR would open front contact 175, and thereby cause the extinguishing of lamp 2-7WFK through the medium of a communication system.

From the mode of operation which has just been described with respect to the control of the traffic direction indicator lamps, it is believed to be readily apparent that the operator is kept well informed as to the condition of the traffic direction relays in the field under all conditions, even under conditions involving back-up train movements. When back-up train movements are involved, the energization of both indicator lamps 2-7WFK and 2-7EFK at the control office indicates an out-of-correspondence condition of the traffic direction relays for the respective ends of the stretch of track, and in accordance with such indication, it is brought to the attention of the operator that he must depress the cancel button 2-7CB after the stretch of track has become unoccupied to cause the reestablishment of a single direction of traffic through the stretch as selected by the position of the traffic direction lever 2-7FL.

From the description as it has been set forth it is believed to be readily apparent that the system is symmetrical in its operation for both directions of traffic, and it is therefore to be understood that the apparatus and mode of operation described specifically with respect to one direction of traffic are typical of similar conditions for the opposite direction of traffic.

Modifications.—It is to be understood that the system can be modified from that which has been described in that the means for governing the traffic direction relays manually can vary to considerable extent in accordance with the requirements of practice. In some cases it may be desirable to control the traffic direction relays at the respective field stations by a code communication system such as shown, for example, in the patent to Judge et al., No. 2,082,544, dated June 1, 1937; by direct wire control, where the control office is relatively close to the field stations; or by direct lever control of the manually controlled traffic direction relays for the respective field stations where an operator is present at each end of the stretch of track as could well be the case if the stretch of track were to extend through a tunnel, or over a bridge, with an interlocking plant at each end thereof. Under the last named condition, the track layout and the control of the signals at the respective field stations would necessarily be modified. The traffic direction relays upon control from the control office would be energized directly from a traffic control lever, and the back contact of the relay CR at each of the field stations would be replaced by a normally closed contact of a correspondence button CB. By such an arrangement it would be required that the operators at the respective ends of the stretch of track communicate with each other by telephone in order to most effectively control the direction of traffic in order that their traffic direction levers could respectively be maintained on correspondence with each other.

Another manner in which the traffic control system provided by this invention can be modi-

fied in accordance with the requirements of practice in a coded centralized traffic control system is to employ the signal control codes for reaching out to the field station in advance for establishing the desired direction of traffic throughout the stretch of track in advance of the signal to be cleared. Such a system of controlling the traffic direction relays by the signal control codes can be accomplished with slight modification according to the teachings of my prior application, Ser. No. 365,669, filed November 14, 1940, or the prior application of Preston, Ser. No. 439,520, filed April 18, 1942.

Having described a centralized traffic control system for a particular stretch of trackway as one embodiment of the present invention, it is desired to be understood that this form is selected to facilitate in the disclosure of the invention, rather than to limit the number of forms which the invention may assume, and it is to be further understood that various adaptations, alterations and modifications may be applied to the specific form shown as required in practice, without in any manner departing from the spirit or scope of the present invention except as limited by the appending claims.

What I claim is:

1. In a coded track circuit signaling system for a stretch of single track having signals at opposite ends governing train movement into the stretch, a code following track relay at each end of the stretch for governing the indications of the associated signal, a code sending means associated with each end of said stretch, said code sending means being effective when actuated to transmit code pulses over the track rails of the stretch toward the opposite end for governing the indications of the signal at that end, said code sending means when actuated remaining effective until automatically restored, means responsive only to energization of the corresponding track relay for a prolonged time interval for automatically restoring the corresponding code sending means, and means manually operable from a distant control office for first energizing the track rails at either selected end of the stretch for such prolonged time interval and then rendering effective the corresponding code transmitting means.

2. In a coded track circuit signaling system for a stretch of single track between two passing sidings, a head-block signal at each end of the stretch, driven code transmitting means at each end of the stretch effective to apply driven code pulses to the rails of the stretch when once rendered active until restored to an inactive condition to thereby govern the indications of the head-block signal at the opposite end of the stretch, means associated with each driven code transmitting means and responsive only to steady energy received for a predetermined time over the track rails of the stretch for causing that driven code transmitting means to be rendered inactive, and manually governed means for selectively rendering the code transmitting means active at one end or the other of said stretch so as to normally maintain coding in said stretch in the direction used for the last train movement, said manually governed means acting upon the selection of a driven code transmitting means at the end of said stretch opposite to the end at which a code transmitting means is then active for initially applying steady energy for a predetermined time to the rails of said stretch at such newly selected end, and then cause said

driven code transmitting means at that end to apply driven code pulses, whereby the driven code transmitting means previously rendered active is caused to be rendered inactive and permit its associated signal to be controlled by driven code pulses received from the opposite end of the stretch.

3. In a coded track circuit signaling system for a stretch of single track between two passing sidings, signal at each end of the stretch, driven code transmitting means at each end of the stretch effective to apply driven code pulses to the rails of the stretch when once rendered active until restored to an inactive condition to thereby govern the indications of the signal at the opposite end of the stretch, means associated with each driven code transmitting means and responsive only to a clear-out impulse of substantially greater duration than a driven code impulse as received over the rails of said stretch for causing that driven code transmitting means to be rendered inactive, and traffic direction control means at each end of the stretch responsive to manual control so as to be rendered active at either selected end of the stretch to apply a clear-out impulse to the rails of said stretch for a substantially greater duration than a driven code impulse and thereafter render the corresponding driven code transmitting means active, whereby the active driven code transmitting means at one end of the stretch may be rendered inactive from the opposite end of the stretch only provided said stretch is not occupied by a train.

4. In a coded track circuit signaling system, a stretch of track including an end section adjacent a track switch, a home signal governing traffic over the track switch, a distant signal governing traffic over said end section toward said home signal, driven code transmitting means at said home signal at times manually initiated for transmitting a driven code over the rails of said end section to govern the indication of said distant signal, inverse code transmitting means at the distant signal responsive to said driven code in the absence of a train in said end section for transmitting inverse code pulses between said driven code pulses to said home signal over the rails of said end section, means at said distant signal for at times applying a relatively long impulse to the rails of said end section, code receiving means at said home signal comprising a code following track relay, front and back contact track repeater relays both picked up during the reception of said inverse code pulses by said track relay for distinctively indicating the absence of a train in approach to said home signal, and a slow pick-up relay controlled by a back contact of said back contact repeater and a front contact of said front contact repeater so as to be energized only during the reception of said relatively long energy impulse, said slow pick-up relay acting when picked up to render said driven code transmitting means inactive until again manually initiated.

5. In a coded track circuit signaling system, a code receiving means comprising a code following track relay connected across the rails of a stretch of track, a slow-acting front contact repeater relay energized each time said code following track relay is picked up, a slow-acting back contact repeater relay energized each time said code following track relay is dropped away providing said front contact repeater is picked up, a clear-out relay having a slow pick-up and a quick release period, circuit means for said

clear-out relay controlled through front and back contacts respectively of said front contact repeater and said back contact repeater to thereby be energized when said code following track relay is maintained picked up for a prolonged period of time, signaling means controlled in accordance with the code received by said code following track relay while both said front and back contact repeater relays are picked up, and other means distinctively controlled by said clear-out relay when it is energized in response to a prolonged energization of said code following track relay.

6. In a coded track circuit signaling system of centralized traffic control, a stretch of track including a plurality of track sections, signals at intervals for governing traffic through the stretch in opposite directions, coding direction control means at each signal location, manually controlled means for initially applying a relatively long energy pulse across the rails at either selected end of the stretch to successively condition each of said coding direction control means for the corresponding direction and thereafter apply driven code pulses in the same direction for governing indications of a signal to govern train movement in the opposite direction, and code sending means at each signal location governed by the associated coding direction control means when thus conditioned for supplying a driven code to the track section in the rear of the signal at a rate depending upon the condition of occupancy of the section in advance of the signal.

7. In a coded track circuit signaling system of centralized traffic control, a stretch of track including a plurality of track sections, signals at intervals for governing traffic through the stretch in opposite directions, coding direction control means at each signal location, manually controlled means for initially applying a relatively long energy pulse across the rails at either selected end of the stretch to successively condition each of said coding direction control means for the corresponding direction and thereafter apply driven code pulses in the same direction for governing indications of a signal governing train movement in the opposite direction, and means associated with each signal and governed by the associated coding direction control means for applying inverse codes to the section in which driven codes are coming toward the signal and applying driven codes to the section on the opposite side of the signal.

8. In a coded track circuit signaling system for railroads for a stretch of track divided into a plurality of track sections, each section having signals for governing traffic in both directions, driven code transmitting means at each end of each of the track sections effective when rendered active to transmit code impulses through the track rails toward the opposite end of the track section, means manually controlled from a distant point to transmit a prolonged impulse from either selected end of the stretch through the track rails toward the opposite end of the stretch, and effective upon the termination of said prolonged impulse to render said driven code transmitting means at that end active for the transmission of a code through the track rails in the same direction, coding direction control means at the adjacent ends of the track sections responsive to the transmission of said prolonged impulse through the track rails of one section toward such adjacent end for repeating such prolonged impulse through the track rails of the adjacent section in

a corresponding direction, said coding direction control means being conditioned by such prolonged impulse to render effective one of the associated code transmitting means to provide 5 driven code pulses in one of the associated track sections in the same direction as said prolonged impulse, and signal control means for each of the signals for causing such signal to indicate proceed only if a track circuit code is transmitted 10 through the track rails in the direction of such signal.

9. In a coded track circuit signaling system, a stretch of track having head-block signals at each end for governing train movement into the stretch, an intermediate signal governing traffic toward one end, manually governed means for transmitting a driven code from either selected end of the stretch through the track rails for clearing the head-block signal at the opposite end, means associated with said intermediate signal and acting when rendered effective by the reception of driven code at that signal to transmit driven code toward the opposing head-block signal, manually controlled means effective while a train is in the stretch for applying a long period 20 of energization to the track rails at said end of the stretch having said head-block signal opposing said intermediate signal for rendering said code transmitting means at the intermediate signal ineffective and then applying a driven code 25 to the track rails in a direction to clear said intermediate signal, whereby the intermediate signal may be cleared for a train in the stretch to make a back-up movement.

10. In a coded track circuit signaling system for railroads for a stretch of track having signals at the ends for governing traffic in both directions, driven code transmitting means at each end of the stretch effective when rendered active to transmit code impulses through the track rails toward the opposite end of the stretch, manually controlled means for each end of the stretch for causing the transmission of a prolonged impulse through the track rails toward the opposite end of the stretch irrespective of an opposing driven code, said means being effective upon the termination of said prolonged impulse to render said driven code transmitting means at that end active for the transmission of a driven code through 40 the track rails in the same direction, means at each end of said stretch responsive to the reception of said prolonged impulse from the opposite end of the stretch for rendering the code transmitting means at that end inactive for the transmission of driven code, and signal control means 45 for each of the signals for causing such signal to indicate proceed only if a track circuit code is received through the track rails from the opposite end of the stretch, whereby a driven code transmitting means can be manually rendered 50 inactive only if the stretch of track is unoccupied.

11. In a coded track circuit signaling system for railroads having a stretch of track with signals at the opposite ends for governing the entrance of traffic into said stretch, driven code transmitting means at each end of the stretch effective when set into operation to transmit driven code impulses through the track rails toward the opposite end of the stretch, a manually controlled traffic direction lever in a control office 55 effective to transmit a directional control to either selected end of the stretch when moved to a corresponding position, means at each end of the stretch responsive to the reception of a directional control for causing the transmission of 60

a prolonged energy impulse through the track rails of the stretch towards the opposite end irrespective of an opposing driven code, said means being effective upon the termination of said prolonged energy impulse to set the corresponding driven code transmitting means into operation to transmit a driven code through the track rails in the same direction, means at each end of the stretch responsive to the reception of a prolonged energy impulse from the opposite end of the stretch for restoring the corresponding driven code transmitting means at that end to an inactive condition, signal control levers at the control office for transmitting a signal clearing control to either selected signal, and signal control means for each signal responsive to a signal clearing control for causing the corresponding signal to indicate proceed only providing a driven code is received over the track rails from the opposite end of the stretch, whereby the direction of driven code transmission can be manually reversed by the operation of said traffic direction lever only providing the stretch of track is not occupied by a train.

12. In a coded track circuit signaling system, a stretch of track including a plurality of track sections, signals at intervals for governing traffic through the stretch in opposite directions, said signals being located at points along the track where the successive track sections join, manually controlled means for initially applying a relatively long energy impulse across the rails at either selected end of the stretch and thereafter apply driven code impulses to the rails at the corresponding end of the stretch, coding direction control means at each signal location responsive to the reception of a prolonged energy impulse in either track section joining at that signal location for repeating a corresponding prolonged energy impulse in the other track section, whereby the manual initiation of a relatively long energy impulse at either end of the stretch causes such impulse to be repeated into each of the successive track sections of the stretch, means associated with each signal and governed by the associated coding direction control means and the reception of the driven code in advance of that signal for applying driven code to the section in the rear of that signal in accordance with the indications thereof, whereby the signals throughout the stretch are controlled for traffic in one direction or the other depending upon the last direction in which a prolonged impulse is transmitted.

13. In a coded track circuit signaling system, a stretch of track including an end section at each end adjacent a track switch at that end, a home signal at each end governing traffic over the corresponding track switch, a distant signal for each end section governing traffic toward the associated home signal, a head-block signal at each end of the stretch for governing the entrance of traffic into the stretch at that end, driven code transmitting means at each of said home signals manually initiated for transmitting driven code pulses over the rails of said stretch to govern the indications of the associated distant signal and the head-block signal at the opposite end of the stretch, inverse code transmitting means at each distant signal responsive to the reception of driven code pulses from its associated home signal for transmitting inverse code pulses toward such home signal, manually controlled means at each home signal for at times applying a relatively long energy impulse

to the rails of said stretch and then initiating the associated driven code transmitting means into operation, means associated with each home signal distinctively responsive to said relatively long impulse for rendering the associated driven code transmitting means inactive until again manually initiated, whereby the driven code transmitting means at either selected end of the stretch may be manually initiated, code receiving means at each home signal responsive to the code pulses of either a driven code or an inverse code, a track occupancy indication means associated with each home signal and controlled by its associated code receiving means so as to indicate the presence of a train in the associated end section when such code receiving means is rendered inactive by reason of the occupied condition of such associated end section, and means associated with each track occupancy indication means effective to temporarily maintain said track indication means in its nonoccupied indicating condition during the application of the prolonged energy impulse at its corresponding home signal location.

14. In a coded track circuit signaling system for railroads, a stretch of track having a double intermediate signal location for governing traffic in opposite directions and located at a point where the stretch is divided into two separated track sections by suitable insulated joints, manually governed means for applying a relatively long energy impulse followed by the application of a driven code to either selected extreme end of the stretch, and coding direction control means associated with said intermediate signal location responsive to the relatively long energy impulse to either track section for causing the opposing intermediate signal at that location to be responsive to the ensuing driven code, said coding direction control means also causing a driven code to be applied to the track section in the rear of that signal in accordance with its indications.

15. In a coded track circuit signaling system for a stretch of single track divided into a plurality of track sections, a head-block signal at each end of the stretch governing train movement into the stretch, intermediate signals at intervals for governing train movement in opposite directions through the stretch, code sending means for each end of each track section, code direction means for each signal location operable to govern the associated code sending means and determine the direction of transmission of signal control codes from that signal location, means manually controlled from a distant control office for selectively conditioning said head-block signals to clear in response to the reception of a signal control code, a traffic lever in said control office manually operable to different positions for opposite directions of traffic, and means including said traffic lever for energizing the track rails at either selected end of the stretch then receiving code to act over the track rails of the stretch and operate said code direction means to reverse the direction of coding in said track sections insofar as the stretch is unoccupied.

16. In a coded track circuit signaling system for a stretch of single track, having a signal at each end governing train movement into the stretch, coding means for each end of the stretch operable to send code pulses toward the opposite end for governing the clearing of the signal at that end, manually operable means in a distant control office for selectively governing the clear-

ing of said signals in response to the reception of code, a separate manually operable traffic lever in said control office movable to different positions in accordance with the desired direction of traffic, and means governed over line wires connecting said control office with both ends of said stretch in accordance with the position of said traffic lever for transmitting current pulses over the track rails of said stretch to render ineffective the coding means at either end of the stretch.

17. In a coded track circuit signaling system for single track railroads, a stretch of single track between passing sidings, head-block signals at the ends of said stretch for governing the entrance of traffic into the stretch, code transmitting means associated with each end of said stretch for transmitting pulses of energy towards the opposite end, traffic lever in a remote control office manually operable to different positions in accordance with the direction of traffic desired, means for each end of the stretch governed by the movement of the traffic lever to a corresponding position for acting over the track rails of the stretch to stop operation of the code transmitter at the opposite end of the stretch and also acting to render effective the associated code transmitting means, and means manually controlled from a remote control office for governing the clearing of said head-block signals.

18. In a coded track circuit signaling system for a stretch of track divided into a plurality of track sections, signals for governing train movement into and through said stretch in both directions, coding means for the respective track sections operable to transmit driven code pulses in either manually selected direction for governing clearing of signals for one direction of traffic, means for transmitting inverse code pulses in the track rails of certain track sections of said stretch during the off intervals between the driven code pulses then existing in those track sections, means manually controlled from a distant control office for governing the direction of coding in said track sections by transmitting over the track rails from the end of the stretch then receiving driven code to the opposite end of the stretch an impulse distinctive from said inverse code pulses, and code responsive means for each end of said stretch responsive to inverse code pulses transmitted toward that end.

19. In a coded track circuit signaling system for a stretch of track divided into an end track section at each end of the stretch and an intermediate track section, code transmitting means for the respective track sections operable to transmit driven code pulses over the track rails of said track section for one manually selected direction of traffic, means for transmitting inverse code pulses during the off intervals of the driven code pulses in the intermediate track section and one end track section for a given direction of driven code transmission in these track sections, said means transmitting inverse code pulses in either

end track section being governed by the inverse code pulses in the intermediate track section, manually controlled means for reversing the existing direction of driven code pulses in all of said track section by applying to the track rails of the stretch at the end then receiving driven code an energization distinctive from said inverse code pulses, and means at each end of the stretch responsive to the inverse code pulses being transmitted toward that end for detecting when a train approaching that end has advanced into the intermediate track section.

20. In a coded track circuit signaling system for a stretch of track divided into a plurality of track sections, a signal at each end of said stretch governing train movement into the stretch, coding direction control means associated with the ends of said track sections and operable to different conditions to conform with a selected direction of traffic, coding means for the respective track sections governed by the associated code direction control means to transmit driven code pulses over the track rails of said track sections for one selected direction of traffic

25 and inverse code pulses in certain of said track sections during the off intervals of the driven code pulses therein, and means manually controlled from a distant control office for transmitting over the track rails of the stretch current pulses distinctive from said inverse code pulses to govern said coding direction control means at the ends of said track sections to establish driven code transmission for either selected direction of traffic, and code responsive means for each end of said stretch energized by the inverse code pulses received at that end.

21. In a coded track circuit signaling system for a stretch of track divided into a plurality of track sections, a signal at each end of the stretch governing train movement into the stretch, intermediate signals at intervals for governing train movement in opposite directions through the stretch, code transmitting means for the respective track sections operable to transmit driven code pulses over the track rails of said track sections for one selected direction of traffic, means for transmitting inverse code pulses in certain of said track sections during the off intervals of the driven code pulses therein, coding direction control means associated with each of said intermediate signals for governing the transmission of driven and inverse code pulses in the adjoining track sections, means manually controlled from a distant control office for determining the direction of driven code transmission in said track sections by transmitting over the track rails impulses distinctive from said inverse code pulses to govern said coding direction control means associated with said intermediate signals, and code responsive means at each end of the stretch energized by the reception of either driven code or inverse code pulses at the corresponding end of the stretch.

THOMAS J. JUDGE.
